UNITED STATES PATENT OFFICE.

FRANK L. BURDICK, OF STURGIS, MICHIGAN, ADMINISTRATOR OF LEO J. BURDICK, DECEASED, ASSIGNOR TO BURDICK-CORBIN COMPANY, OF HARTFORD, CONNECTICUT.

CHECK-REGISTER.

No. 861,259.

Specification of Letters Patent.

Patented July 30, 1907.

Application filed January 5, 1905. Serial No. 239,830.

To all whom it may concern:

Be it known that LEO J. BURDICK, now deceased, but during his lifetime a citizen of the United States, and a resident of the city of Sturgis, county of St.

5 Joseph, State of Michigan, did invent certain new and useful Improvements in Check-Registers, of which the following is a specification.

This invention relates to improvements in check registering-mechanisms.

10 The objects of this invention are: First, to provide an improved check registering mechanism by which checks of different denominations or fixed values introduced therein are registered. Second, to provide an improved check registering mechanism by which 15 the value of each check introduced is indicated as an item, and also the total value of the checks introduced registered. Third, to provide an improved check registering mechanism by which checks of different denominations and fixed values are registered, which 20 is very simple and compact in structure and economical to produce. Fourth, to provide an improved check register which is simple and easy to operate and not likely to get out of repair.

Further objects and objects relating to structural 25 details will definitely appear from the detailed description to follow.

The objects of this invention are accomplished by the devices and means described in the following specification.

30 The invention is clearly defined and pointed out in the claims.

A structure embodying the features of this invention is clearly illustrated in the accompanying drawings forming a part of this specification, in which—

35 Figure 1 is an end elevation of a structure embodying the features of this invention, looking from the right of Figs. 2 and 3, the crank B' being removed and the casing shown in vertical transverse section to expose the internal mechanism. Fig. 2 is a front elevation 40 view with the casing door A' removed. Fig. 3 is a transverse detail sectional view taken on line 3-3 of Fig. 1, Fig. 4 is an edge view of the number wheel I', showing the transfer teeth j' thereof and also the notch j' therein. Fig. 5 is a side elevation view of the number 45 wheel I', showing its relation to the pinion J''. Fig. 6 is a detail sectional view taken on line 6-6 of Fig. 1, showing the means for shifting the transfer pinions J' into and out of engaging position. Fig. 7 is a detail end elevation looking from the right of Fig. 1, the location of the several shafts being indicated theron. Fig. 50 Fig. 8 is a detail side elevation view of the check-holder and carrying wheel C. Fig. 9 is a detail plan view of the wheel C with the check holder in position thereon. Fig. 10 is a detail elevation view of the wheel C and 55 check holder C', looking from the right of Figs. 8 and 9.

Fig. 11 is a detail elevation view of the locking dogs L' for the toothed wheels F and F'. Fig. 12 is a detail sectional view taken on a line corresponding to line 12-12 of Fig. 11. Fig. 13 is an end view of one of the checks M. Fig. 14 is a plan view thereof. 60

In the drawings the sectional views are taken looking in the direction of the little arrows at the ends of the section lines, and similar letters of reference refer to similar parts throughout the several views.

Referring to the drawing, a casing A is provided to 65 suitably support and protect the mechanism. The casing is provided with a door A'.

A rockshaft B is arranged horizontally in the casing with one of its ends projecting therethrough. On this projecting end of the rockshaft B is a crank B'. Stops 70 b b' are provided to limit the stroke of this crank and thereby limit the movement of the rock shaft B. A check holder carrying wheel C is secured upon the rock shaft B. C' is the check holder. The check holder C' is provided with arms C'' which are pivoted to the 75 wheel C at c'. There is a slot-like opening through the rim of the wheel C to receive the check holder, which is arranged transversely thereto, as clearly appears in Figs. 8, 9 and 10. A spring c'' secured to the rim of the wheel C and to the inner end of the check holder, holds 80 the check holder normally outward.

Arranged at each side of the wheel C are toothed wheels F and F'. The check holder C is provided with laterally projecting arms c, adapted when the holder is 85 in its inner position to engage these toothed wheels F and F'. These toothed wheels F and F' are carried by the sleeves E and E' respectively. These sleeves E and E' are mounted on the shaft B. The toothed wheels F and F' are each provided with forty teeth. One half a revolution will register one dollar or one hundred cents. Each tooth will therefore represent one twentieth of one hundred cents or five cents. The wheel F drives the total registering mechanism having number wheel I' I'' and I''', and the wheel F' drives the item or purchase indicating wheel G'. (See Figs. 90 1 and 2.) This item wheel G' is mounted on the shaft G. The shaft G is provided with a pinion e which meshes with the gear E''' on the sleeve E' by which the toothed wheel F' is carried. Thus connected the movement of the wheel F' is imparted to the item or purchase indicating wheel G'. The item wheel G' is provided with two sets of figures so arranged in relation to each other that corresponding figures will be visible in the front and rear windows s s' at the same time. This enables the amount of the item or purchase to be 95 observed by both the salesman or operator at the front of the machine, and by the purchaser at the rear thereof. The gears E''' and e are so proportioned that the item wheel is advanced from "0" to "100" at each half-revolution of the wheel F'. 100

As before stated, the total registering mechanism is driven by the toothed wheel F. To accomplish this a gear E'' adapted to mesh with the pinion e'', is mounted on the sleeve E by which the wheel F is carried. 5 The pinion e'' is mounted on the hub i of the units number wheel I'. The number wheels I' I'' and I''' are revolvably mounted on the shaft I. The shaft I is arranged parallel with the shaft B. The inner end of the shaft I is supported by the bracket or standard a, 10 and its outer end is supported by the casing A. The gears E'' and e'' are proportioned 2 to 1, so that the units wheel I' is caused to make one complete revolution to each one-half revolution of the toothed wheel F, which as before stated, has forty teeth, which teeth correspond to the number spaces of the number wheels. 15

The unit of value in the structure illustrated is 5, and the units wheel I' is divided into 20 spaces so that when it has made one complete revolution it registers 100 or one dollar. The number wheel I' is provided 20 with a tooth j' adapted to engage the transfer pinion J', so that at each revolution of the units number wheel the transfer pinions is advanced one step. The transfer pinion J' meshes with the transfer gear J on the hub i of the number wheel I''. The number wheel I'' is provided with two teeth j' arranged in proper relation to the two sets of figures, which are adapted to engage the transfer pinion J' of the number wheel I''', so that the number wheel I''' is advanced one step or space at each half revolution of the number wheel I''. This number wheel I''' is divided into twenty steps numbered 30 from 0 to 19. With the number wheels thus arranged to register \$199 $\frac{9.5}{100}$ —(\$199.95). The transfer pinions J' J'' are slidably mounted on the shaft K, so that they are shifted into and out of mesh with gears J. This is 35 accomplished by the lever K' which is mounted on the upper end of the post K''. The lever K' is provided with an arm k projecting between the pinions J', and with arms k' which engage the outer end thereof. The engaging portions of these arms are curved to permit the shifting of the lever and at the same time serve to keep the pinions properly spaced on the shaft. To 40 retain the lever in its adjusted position, one of the arms k' is provided with upwardly projecting lugs k'' adapted to engage the notches k''' in the under side of the 45 shaft K. (See Fig. 2.)

To prevent the overthrow of the number wheels, the hubs of the pinion J' are toothed or provided with pinions J'', spaced to engage the peripheries of the number wheels I' and I''. (See Fig. 5.) The peripheries of 50 these number wheels I' I'' are slotted at j opposite the teeth j' (see Fig. 4) to allow the pinion to turn or advance one step when this point is reached. The number wheels I' I'' are beveled at i' so that when the pinions J' are shifted the pinions J'' are disengaged from 55 the number wheels so that the number wheels may be freely revolved to reset them or return them to the original position. With the parts thus arranged, the actuation of the toothed wheel F is registered by the number wheels I' I'' and I''', and the actuation of the 60 toothed wheel F' is registered by the item or purchase wheel G'. As before stated, the wheels F F' are rotatably secured to the shaft B by means of the check holder C' and the wheel C by which it is carried. When the check holder is in its inner position it engages the 65 teeth of these wheels F and F' so that when the rock

shaft B is actuated the wheels F and F' are advanced according to the time of the engagement of the check holder therewith. As this engagement of the check holder is determined by the denomination of the fixed value of the check, it is evident that the value of the 70 check is registered.

To cause the check holder to engage the wheels F and F' at the proper point, curved cam plates II and II', 75 II' are supported in position to engage the checks, as M, (see Figs. 13 and 14) as they are carried by the check holder. The cam plate II is arranged in the upper rear portion of the casing opposite the check holder carrying wheel C, and the plates II' II' are arranged side by side below and to each side of the cam plate II. Supporting posts or standards a a'' are provided for these cams.

The checks M are provided with notches m m' adapted to engage the cams of these plates. The depth of the notches is regulated to engage the proper cam or cams for registering the particular amount or value of 85 the check. The check holder will engage the wheels F F' corresponding to the cam or cams engaged. The plate II is provided with cam projections h h' h'', and the plates II' which are substantial duplicates, are provided with cam projections i i' i'' i''''. These cams are 90 so spaced and arranged as to cause the check holder to engage the wheels F F' and retain the holder in engagement therewith, or require it to cause the proper actuation thereof. For example, the cam projection i''' is the 5 or units projections, and when a check of 95 that value or denomination is introduced it is not engaged by the cam plates until the cam projection i''' is reached. The projections i''' engaging the check forces the holder inward so that the lugs c engage the toothed wheels F and F' and thereby lock them to the 100 wheel C. As the check is carried forward it snaps off the ends of the cam plates II' and drops into the drawer P, thus releasing the holder, which is thrown outwardly by the spring e'', thereby releasing the wheels F and F' which have only been advanced one step. 105 This, through the mechanism described, registers the value of the check and also shows the value of the check by the item or purchase wheel G', both to salesman and to the purchaser.

To prevent the overthrow of the wheels F and F', 110 the dogs L L' are provided. These dogs are secured together by the cross-piece L'' and are adapted to engage the wheels F and F' at the same time. The dogs L' are supported on the rock-shaft L (see Figs. 1, 2 and 11 and 12.) These dogs L are held normally out of engagement with the wheels F and F' by the spring r which is secured at one end of the standard a, and at its other end to the dogs L' by the pins r' between which it is arranged. (See Figs. 11 and 12.) The dogs L' are thrown into engagement with the wheels F and F' by 115 pins n on the check holder carrying wheel C, which successively engage the lug or projection l on the dogs. These pins are so arranged on the wheel C as to engage the lug l of the dogs at the point of release of the wheels F and F' by the check holder—that is, at the ends of 120 the cams II and II'. The stops b and b' allow the rotation of the rockshaft far enough to bring the check holder well past the cams. When the check holder carrying wheel reaches the limit of its forward movement it is locked in that position by the dog D which is piv- 125 130

oted on the wheel C. (See Fig. 8.) A spring d holds the dog normally outward. A stop D' is provided for this dog. (See Figs. 2 and 8.) This dog, when in its engaging position, is located beneath the check chute so that the introduction of a check disengages the same, allowing the wheel C to be returned to its initial position, when the check drops into the holder C'. The lug l of the locking dogs L' is inclined so that the pins n engage the under side thereof in the forward movement of the wheel to throw the dogs into engagement, and on the return movement the lugs n engage the top side of the lug l so that the dogs are thrown away from the wheels instead of into engagement. On the return movement of the check holder carrying wheel, the item or purchase indicating wheel G' is returned to its initial position by the lug or pin n' on the wheel C which engages the lug or pin n'' on the toothed wheel F'. (See Figs. 2 to 9). The forward rotation of the wheel C brings the check into engagement with its proper cam projection or projections thereby forcing the lugs c into engagement with the toothed wheels F F' so that they are advanced a proper distance. The cam projections t t' t'' t''' and t'''' of the cam plates H' are the 25, 20, 15, 10 and 5 cent projections respectively, and the projections h h' h'' of the cam plate H, coacting with these cam projections register checks of any value from 30 cents to one dollar, for example, a check of the value of 30 cents will be engaged by the projections h'' and the projections t'''', the projections h'' holding the check holder into engagement with the toothed wheels to cause them to register 25 cents, and the projections t'''' holding the same in engagement to cause it to register 5 cents the 30 cent check being provided with notches of the right depth to engage the cam plates at these points. A check of the value of 60 cents would be engaged by the projections h' and h'' and by the projections t''' and t'''', the projections h' and h'' holding the check holder in its engaging position to register 50 cents and the projections t''' and t'''' holding the check holder in its engaging position to register 10 cents. A check of the value of 80 cents would be engaged by the cam projections h, h' and h'' and t'''', and so on the notches m and m' of the checks of the different denominations being properly regulated to secure the engagement by cam plates at the proper point. The checks M are corrugated as illustrated, to prevent the introductions of slugs or fraudulent checks not adapted to the mechanism. The mechanism could obviously be made to use plain checks.

50 A cash drawer P' is arranged below the check drawer P for convenience, and it is intended that a sum equal to the face value of the checks shall be deposited therein, the amount shown by the register indicating the amount of the sales.

55 This improved check register is very simple and easy in operation and is not likely to get out of repair. This improved check register has been illustrated and described in what is believed to be its most desirable form, on account of its simplicity and economy. It will be evident, however, to those skilled in the art to which this invention relates, that it is capable of considerable structural variation without departing from this invention, and it is desired to claim it specifically, as here illustrated, as well as broadly.

60 Having thus described the invention, what is

claimed as new and desired to be secured by Letters Patent, is:

1. The combination of a suitable casing; a shaft; a check holder carrier carried by said shaft; a pair of toothed wheels F and F' arranged at each side of said check holder carrier; a check holder yieldingly secured to said check carrying wheel adapted to engage the said toothed wheels when in its inner position; a spring adapted to hold said check holder normally outward; a cam plate having a plurality of cam projections thereon, adapted to engage the checks as they are carried forward by said check holder, whereby said check holder is thrown into engagement with the toothed wheels at a predetermined point or points in the movement of said check holder; locking dogs for said toothed wheels; a spring for holding said dogs normally out of engagement; trip pins on said check holder carrier for said dogs, adapted to engage them to throw them into engagement with said toothed wheels at the points of their release by the check holder; a locking dog for said check holder carrier; a spring adapted to hold said dog normally outward; a stop adapted to engage said dog when said carrier is at the limit of its movement, said locking dog being then in position to be disengaged by the introduction of a check; a suitable registering mechanism; driving connections from the toothed wheel F to the said registering mechanism; an item or purchase indicating number wheel having two sets of corresponding figures thereon, arranged so that the corresponding figures will appear at the same time in the front and rear windows of the casing; driving connections from the toothed wheel F' to said item or purchase indicating number wheel; and connections for returning said item or purchase indicating number wheel to its initial position on the return movement of said check holder carrier, all coacting for the purpose specified.

2. The combination of a suitable casing; a shaft; a check holder carrier carried by said shaft; a pair of toothed wheels F and F' arranged at each side of said check holder carrier; a check holder yieldingly secured to said check carrying wheel adapted to engage the said toothed wheels when in its inner position; a spring adapted to hold said check holder normally outward; a cam plate having a plurality of cam projections thereon adapted to engage the checks as they are carried forward by said check holder, whereby said check holder is thrown into engagement with the toothed wheels at a predetermined point or points in the movement of said check holder; locking dogs for said toothed wheels; a spring for holding said locking dogs normally out of engagement; trip pins on said check holder carrier for said dogs, adapted to engage them to throw them into engagement with said toothed wheels at the points of their release by the check holder; a locking dog for said check holder carrier; a spring adapted to hold said dog normally outward; a stop adapted to engage said dog when said carrier is at the limit of its movement, said locking dog being then in position to be disengaged by the introduction of a check; a suitable registering mechanism; driving connections from the toothed wheel F to the said registering mechanism; an item or purchase indicating number wheel; driving connections from the toothed wheel F' to said item or purchase indicating number wheel; and connections for returning said item or purchase indicating number wheel to its initial position on the return movement of said check holder carrier, all coacting for the purpose specified.

3. The combination of a suitable casing; a shaft; a check holder carrier carried by said shaft; a pair of toothed wheels F and F' arranged at each side of said check holder carrier; a check holder yieldingly secured to said check carrying wheel adapted to engage the said toothed wheels when in its inner position; a spring adapted to hold said check holder normally outward; a cam plate having a plurality of cam projections thereon, adapted to engage the checks as they are carried forward by said check holder, whereby said check holder is thrown into engagement with the toothed wheels at a predetermined point or points in the movement of said check holder; locking dogs for said toothed wheels; a spring for holding said dogs normally out of engagement; trip pins on said check holder carrier

ed to engage the checks as they are carried forward by said check holder, whereby said check holder is thrown into engagement with the toothed wheels at a predetermined point or points in the movement of said check holder; a suitable registering mechanism; driving connections from the toothed wheel F to said registering mechanism; an item or purchase indicating number wheel; and driving connections from the toothed wheel F' to said item or purchase indicating number wheel, all coacting for the purpose specified.

17. The combination of a suitable casting; a shaft; a check holder carrier carried by said shaft; a toothed wheel having forty teeth thereon, arranged at the side of said check holder carrier; a check holder yieldingly secured to
15 said carrier, adapted to engage the said toothed wheel when in its inner position; a cam plate having a plurality of cam projections thereon adapted to engage the checks as they are carried forward by said holder, whereby said check holder is caused to engage said toothed wheel at a predetermined point; a locking dog for said toothed wheel; a spring for holding said dog normally out of engagement; trip pins on said check holder carrier for said dog, adapted to engage it to throw it into engagement with said toothed wheel at the points of its release by the check
20 holder; a locking dog for said check holder carrier; a spring adapted to hold said dog normally outward; a stop adapted to engage said dog when said carrier is at the limit of its movement, said locking dog being then in position to be disengaged by the introduction of a check; a
25 registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into
30 twenty spaces numbered 0 to 19 inclusive; driving connections from the toothed wheel to the said number wheel I'; a transfer mechanism for said number wheels, consisting of pinions J'; a shaft for said pinions on which they are slidably mounted; gears J mounted on the hubs of
35 the number wheels I'' and I'''; teeth j' on said number wheels I' and I''', adapted to engage said pinions J', said number wheel I' being provided with one only of said teeth j' and the number wheel I''' being provided with two; teeth or pinions J'' on the hubs of said pinions J', adapted
40 to engage the peripheries of the said number wheels I' and I''; notches in the peripheries of the said number wheels I' and I'' opposite to said teeth j' to permit the said pinions to advance one step; a lever for shifting the pinions J', having arms engaging the ends of said pinions, said arms having curved engaging portions; and means for securing said lever in its adjusted position, all coacting for
45 the purpose specified.
50

18. The combination of a suitable casing; a shaft; a check holder carrier carried by said shaft; a toothed wheel having forty teeth thereon, arranged at the side of said check holder carrier; a check holder yieldingly secured to said carrier, adapted to engage the said toothed wheel when in its inner position; a cam plate having a plurality of cam projections thereon adapted to engage the checks as they are carried forward by said holder, whereby said check holder is caused to engage said toothed wheel at a predetermined point; a locking dog for said check holder carrier; a spring adapted to hold said dog normally outward; a stop adapted to engage said dog when said carrier is at the limit of its movement, said locking dog being then in position to be disengaged by the introduction of a check; a registering mechanism consisting of number wheels I' I'' and III'', the said wheel I' being divided into twenty spaces numbered 0 to 95 inclusive, the number wheel I'' being divided into twenty spaces numbered in two sets 0 to 9 inclusive, and the number wheel III'' being divided into twenty spaces numbered 0 to 19 inclusive; driving connections from the toothed wheel to said number wheel I'; a transfer mechanism for said number wheels, consisting of pinions J'; a shaft for said pinions on which they are slidably mounted; gears J mounted on the hubs of the number wheels I'' and III''; teeth j' on said number wheels I' and I'', adapted to engage said pinions J'; said number wheel I' being provided with one only of said teeth j' and the number wheel III'' being provided

with two; teeth or pinions J'' on the hubs of said pinions J' , adapted to engage the peripheries of the said number wheels I' and I'' ; notches in the peripheries of said number wheels I' and I'' opposite to said teeth J' to permit the said pinions to advance one step; a lever for shifting the 85 pinions J' , having arms engaging the ends of said pinions, said arms having curved engaging portions; and means for securing said lever in its adjusted positions, all coacting for the purpose specified.

19. The combination of a suitable casing; a shaft; a check holder carrier carried by said shaft; a toothed wheel having forty teeth thereon, arranged at the side of said check holder carrier; a check holder yieldingly secured to said carrier, adapted to engage the said toothed wheel when in its inner position; a cam plate having a plurality of cam projections thereon adapted to engage the checks as they are carried forward by said holder, whereby said check holder is caused to engage said toothed wheel at a predetermined point; a locking dog for said toothed wheel; a spring for holding said dog normally out of engagement; trip pins on said check holder carrier for said dog, adapted to engage it to throw it into engagement with said toothed wheel at the points of its release by the check holder; a registering mechanism consisting of number wheels I' 1' and I'', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connections from the toothed wheel to the said number wheel I'; a transfer mechanism for said number wheels, consisting of pinions J'; a shaft for said pinions on which they are slidably mounted; gears J mounted on the hubs of the number wheels I'' and I'''; teeth j' on said number wheels I' and I'', adapted to engage said pinions J'; said number wheel I' being provided with one only of said teeth j' and the number wheel I'' being provided with two; teeth or pinions J'' on the hubs of said pinions J', adapted to engage the peripheries of the said number wheels I' and I''; notches in the peripheries of the said number wheels I' and I'' opposite to said teeth j' to permit the said pinions to advance one step; a lever for shifting the pinions J', having arms engaging the arms of said pinions, said arms having curved engaging portions; and means for securing said lever in its adjusted positions, all coacting for the purpose specified. 125

20. The combination of a suitable casing; a shaft; a check holder carrier carried by said shaft; a toothed wheel having forty teeth thereon, arranged at the side of said check holder carrier; a check holder yieldingly secured to 130 said carrier, adapted to engage said toothed wheel when in its inner position; a cam plate having a plurality of cam projections thereon adapted to engage the checks as they are carried forward by said holder, whereby said check holder is caused to engage said toothed wheel at a pre-determined point; a registering mechanism consisting of 135 number wheels I' I'' and I''', the said wheel I' being divided into twenty spaces numbered 0 to 95 inclusive, and the number wheel I'' being divided into twenty spaces numbered in two sets 0 to 9 inclusive, and the number 140 wheel I''' being divided into twenty spaces numbered 0 to 19 inclusive; driving connections from the toothed wheel to said number wheel I'; a transfer mechanism for said number wheels consisting of pinions J'; a shaft for said pinions on which they are slidably mounted; gears 145 J mounted on the hubs of the number wheels I'' and I'''; teeth J' on said number wheels I' and I''', adapted to engage said pinions J'; said number wheel I' being provided with one only of said teeth J' and the number wheel I''' being provided with two; teeth or pinions J'' on the hubs 150 of said pinions J', adapted to engage the peripheries of the said number wheels I' and I'''; notches in the peripheries of said number wheels I' and I''' opposite to said teeth J' to permit said pinions to advance one step; a lever for shifting the pinions J', having arms engaging 155 the ends of said pinions; said arms having curved engaging portions; and means for securing said lever in its adjusted positions, all coacting for the purpose specified.

21. The combination of a suitable casing; a shaft; a 160

check holder carrier carried by said shaft; a toothed wheel having forty teeth thereon, arranged at the side of said check holder carrier; a check holder yieldingly secured to said carrier, adapted to engage the said toothed wheel 5 when in its inner position; a cam plate having a plurality of cam projections thereon adapted to engage the checks as they are carried forward by said holder, whereby said check holder is caused to engage the said toothed wheel at a predetermined point; a locking dog for said toothed wheel; a spring for holding said dog normally out of engagement; trip pins on said check holder carrier for said dog, adapted to engage it to throw it into engagement with 10 said toothed wheel at the points of its release by the check holder; a registering mechanism consisting of number wheels I' I'' and I''', the said wheel I' being divided into twenty spaces numbered 0 to 95 inclusive, the number wheel I'' being divided into twenty spaces numbered in 15 two sets 0 to 9 inclusive, and the number wheel I''' being divided into twenty spaces numbered 0 to 19 inclusive; driving connections from the toothed wheel to the said number wheel I'; a transfer mechanism for said number 20 wheels consisting of pinions J'; a shaft for said pinions on which they are slidably mounted; gears J mounted on the hubs of the number wheels I'' and I'''; teeth J' on said number wheels I' and I'', adapted to engage said pinions J', said number wheel I' being provided with one only of 25 said teeth J' and the number wheel I'' being provided with two; teeth or pinions J''' on the hubs of said pinions J', adapted to engage the peripheries of the said number wheels I' and I''; and notches in the peripheries of the said number wheels I' and I'' opposite to said teeth J' to permit the 30 said pinions to advance one step, all coacting for the purpose specified.

22. The combination of a suitable casing; a shaft; a 40 check holder carrier carried by said shaft; a toothed wheel having forty teeth thereon, arranged at the side of said check holder carrier; a check holder yieldingly secured to said carrier, adapted to engage the said toothed wheel when in its inner position; a cam plate having a plurality of cam 45 projections thereon adapted to engage the checks as they are carried forward by said holder, whereby said check holder is caused to engage said toothed wheel at a predetermined point; a locking dog for said check holder carrier; a spring adapted to hold said dog normally outward; a stop adapted to engage said dog when said carrier is at the 50 limit of its movement, said locking dog being then in position to be disengaged by the introduction of a check; a registering mechanism consisting of the number wheels I' I'' and I''', the said wheel I' being divided into twenty spaces numbered 0 to 95 inclusive, the number wheel I'' being divided into twenty spaces numbered in 55 two sets 0 to 9 inclusive, and the number wheel I''' being divided into twenty spaces numbered 0 to 19 inclusive; driving connections from the toothed wheel to the said number wheel I'; a transfer mechanism for said number wheels consisting of pinions J'; a shaft for said pinions on which they are slidably mounted; gears J mounted on the hubs of the number wheels I'' and I'''; teeth J' on said number wheels I' and I'', adapted to engage said pinions J', said number wheel I' being provided with one only of 60 said teeth J' and the number wheel I'' being provided with two; teeth or pinions J''' on the hubs of said pinions J', adapted to engage the peripheries of the said number wheels I' and I''; and notches in the peripheries of the said number wheels I' and I'' opposite to said teeth J' to permit the 65 said pinions to advance one step, all coacting for the purpose specified.

23. The combination of a suitable casing; a shaft; a 70 check holder carrier carried by said shaft; a toothed wheel having forty teeth thereon, arranged at the side of said check holder carrier; a check holder yieldingly secured to said carrier, adapted to engage the said toothed wheel when in its inner position; a cam plate having a plurality of cam 75 projections thereon adapted to engage the checks as they are carried forward by said holder, whereby said check holder is caused to engage the said toothed wheel at a predetermined point; a locking dog for said toothed wheel; a spring for holding said dog normally out of engagement; trip pins on said check holder carrier for said dog, adapted to engage it to throw it into engagement with 80 said toothed wheel at the points of its release by the check holder; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connec-

85 said check holder is caused to engage said toothed wheel at a predetermined point; a locking dog for said toothed wheel; a spring for holding said dog normally out of engagement; trip pins on said check holder carrier for said dog, adapted to engage it to throw it into engagement with said toothed wheel at the points of its release by the check holder; a registering mechanism consisting of number wheels I' I'' and I''', the said wheel I' being divided into twenty spaces numbered 0 to 95 inclusive, the number wheel I'' being divided into twenty spaces numbered in 90 two sets 0 to 9 inclusive, and the number wheel I''' being divided into twenty spaces numbered 0 to 19 inclusive; driving connections from the toothed wheel to the said number wheel I'; a transfer mechanism for said number wheels consisting of pinions J'; a shaft for said pinions on which they are slidably mounted; gears J mounted on the hubs of the number wheels I'' and I'''; teeth J' on said number wheels I' and I'', adapted to engage said pinions J', said number wheel I' being provided with one only of said teeth J' and the number wheel I'' being provided with two; teeth or pinions J''' on the hubs of said pinions J', adapted to engage the peripheries of the said number wheels I' and I''; and notches in the peripheries of the said number wheels I' and I'' opposite to said teeth J' to permit the said pinions to advance one step, all coacting for the purpose specified.

24. The combination of a suitable casing; a shaft; a check holder carrier carried by said shaft; a toothed wheel having forty teeth thereon, arranged at the side of said check holder carrier; a check holder yieldingly secured to said carrier, adapted to engage said toothed wheel when in its inner position; a cam plate having a plurality of cam 110 projections thereon adapted to engage the checks as they are carried forward by said holder, whereby said check holder is caused to engage said toothed wheel at a predetermined point; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive; and the number wheel I''' being divided into twenty spaces numbered 0 to 19 inclusive; driving connections from the toothed wheel to the said number wheel I'; a transfer mechanism for said number wheels consisting of pinions J'; a shaft for said pinions on which they are slidably mounted; gears J mounted on the hubs of the number wheels I'' and I'''; teeth J' on said number wheels I' and I'', adapted to engage said pinions J', said number wheel I' being provided with one only of said teeth J' and the number wheel I'' being provided with two; teeth or pinions J''' on the hubs of said pinions J', adapted to engage the peripheries of the said number wheels I' and I''; and notches in the peripheries of the said number wheels I' and I'' opposite to said teeth J' to permit the said pinions to advance one step, all coacting for the purpose specified.

25. The combination of a suitable casing; a shaft; a check holder carrier carried by said shaft; a toothed wheel having forty teeth thereon, arranged at the side of said check holder carrier; a check holder yieldingly secured to said carrier, adapted to engage the said toothed wheel when in its inner position; a cam plate having a plurality of cam 115 projections thereon adapted to engage the checks as they are carried forward by said holder; whereby said check holder is caused to engage said toothed wheel at a predetermined point; a locking dog for said toothed wheel; a spring for holding said dog normally out of engagement; trip pins on said check holder carrier for said dog, adapted to engage it to throw it into engagement with said toothed wheel at the points of its release by the check holder; a locking dog for said check holder carrier; a 120 spring adapted to hold said dog normally outward; a stop adapted to engage said dog when said carrier is at the limit of its movement, said locking dog being then in position to be disengaged by the introduction of a check; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connec-

- 5 tions from the toothed wheel to said number wheel I'; a transfer mechanism for said number wheels; a lever for shifting the pinions J', having arms engaging the ends of said pinions, said arms having curved engaging portions; and means for securing said lever in its adjusted positions, all coacting for the purpose specified.

6 26. The combination of a suitable casing; a shaft; a check holder carrier carried by said shaft; a toothed wheel having forty teeth thereon, arranged at the side of said check holder carrier; a check holder yieldingly secured to said carrier, adapted to engage said toothed wheel when in its inner position; a cam plate having a plurality of cam projections thereon adapted to engage the checks as they are carried forward by said holder, whereby said 10 check holder carrier; a check holder yieldingly secured to said carrier, adapted to engage the said toothed wheel when in its inner position; a cam plate having a plurality of cam projections thereon adapted to engage the checks as they are carried forward by said holder, whereby said 15 check holder is caused to engage said toothed wheel at a predetermined point; a locking dog for said toothed wheel; a spring for holding said dog normally out of engagement; trip pins on said check holder carrier for said dog, adapted to engage it to throw it into engagement with said toothed wheel at the points of its release by the check holder; a locking dog for said check holder carrier; a spring adapted to hold said dog normally outward; a stop adapted to engage said dog when said carrier is at the limit of its movement, said locking dog being then 20 in position to be disengaged by the introduction of a check; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connections from the toothed wheel to the said number wheel I'; and a transfer 25 mechanism for said number wheels, all coacting for the purpose specified.

26. The combination of a suitable casing; a shaft; a check holder carrier carried by said shaft; a toothed wheel having forty teeth thereon, arranged at the side of said check holder carrier; a check holder yieldingly secured to said carrier, adapted to engage the said toothed wheel when in its inner position; a cam plate having a plurality of cam projections thereon adapted to engage the checks as they are carried forward by said holder, whereby said 30 check holder is caused to engage said toothed wheel at a predetermined point; a locking dog for said toothed wheel; a spring adapted to hold said dog normally outward; a stop adapted to engage said dog when said carrier is at the limit of its movement, said locking dog being then 35 in position to be disengaged by the introduction of a check; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connections from the toothed wheel to the said number wheel I'; and a transfer 40 mechanism for said number wheels, all coacting for the purpose specified.

27. The combination of a suitable casing; a shaft; a check holder carrier carried by said shaft; a toothed wheel having forty teeth thereon, arranged at the side of said check holder carrier; a check holder yieldingly secured to said carrier, adapted to engage the said toothed wheel when in its inner position; a cam plate having a plurality of cam projections thereon adapted to engage the checks as they are carried forward by said holder, whereby said 45 check holder is caused to engage said toothed wheel at a predetermined point; a locking dog for said toothed wheel; a spring for holding said dog normally out of engagement; trip pins on said check holder carrier for said dog, adapted to engage it to throw it into engagement with said toothed wheel at the points of its release by the check holder; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connections from the toothed wheel to the said number wheel I'; and a transfer 50 mechanism for said number wheels, all coacting for the purpose specified.

28. The combination of a suitable casing; a shaft; a check holder carrier carried by said shaft; a toothed wheel having forty teeth thereon, arranged at the side of said check holder carrier; a check holder yieldingly secured to said carrier, adapted to engage said toothed wheel when in its inner position; a cam plate having a plurality of cam projections thereon adapted to engage the checks as they are carried forward by said holder, whereby said 55 check holder is caused to engage said toothed wheel at a predetermined point; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connections from the toothed wheel to the said number wheel I'; and a transfer 60 mechanism for said number wheels, all coacting for the purpose specified.

29. The combination of a suitable casing; a shaft; a check holder carrier carried by said shaft; a toothed wheel having forty teeth thereon, arranged at the side of said check holder carrier; a check holder yieldingly secured to said carrier, adapted to engage said toothed wheel when in its inner position; a cam plate having a plurality of cam projections thereon adapted to engage the checks as they are carried forward by said holder, whereby said 65 check holder is caused to engage said toothed wheel at a predetermined point; a locking dog for said toothed wheel; a spring for holding said dog normally out of engagement; trip pins on said check holder carrier for said dog, adapted to engage it to throw it into engagement with said toothed wheel at the points of its release by the check holder; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connections from the toothed wheel to the said number wheel I'; and a transfer 70 mechanism for said number wheels, all coacting for the purpose specified.

30. The combination of a suitable casing; a shaft; a check holder carrier carried by said shaft; a toothed wheel having forty teeth thereon, arranged at the side of said check holder carrier; a check holder yieldingly secured to said carrier, adapted to engage said toothed wheel when in its inner position; a cam plate having a plurality of cam projections thereon adapted to engage the checks as they are carried forward by said holder, whereby said 75 check holder is caused to engage said toothed wheel at a predetermined point; a locking dog for said toothed wheel; a spring for holding said dog normally out of engagement; trip pins on said check holder carrier for said dog, adapted to engage it to throw it into engagement with said toothed wheel at the points of its release by the check holder; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connections from the toothed wheel to the said number wheel I'; and a transfer 80 mechanism for said number wheels, all coacting for the purpose specified.

- are carried forward by said holder, whereby said check holder is caused to engage said toothed wheel at a predetermined point; a registering mechanism consisting of number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; driving connections from the toothed wheel to said number wheel I'; and a transfer mechanism for said number wheels, all coacting for the purpose specified. 5
33. The combination of a suitable casing; a shaft; a check holder carrier carried by said shaft; a toothed wheel arranged at the side of said check holder carrier; a check holder yieldingly secured to said carrier, adapted to engage said toothed wheel when in its inner position; a cam plate having a plurality of cam projections thereon adapted to engage the checks as they are carried forward by said holder, whereby said check holder is caused to engage said toothed wheel at a predetermined point in its movement; a locking dog for said toothed wheel; a spring for holding said dog normally out of engagement; trip pins on said check holder carrier for said dog, adapted to engage it to throw it into engagement with said toothed wheel at the points of its release by the check holder; a locking dog for said check holder carrier; a spring adapted to hold said dog normally outward; a stop adapted to engage said dog when said carrier is at the limit of its movement, said locking dog being then in position to be disengaged by the introduction of a check; a suitable registering mechanism; and driving connections from said toothed wheel to said registering mechanism, 10 for the purpose specified. 10
34. The combination of a suitable casing; a shaft; a check holder carrier carried by said shaft; a toothed wheel arranged at the side of said check holder carrier; a check holder yieldingly secured to said carrier, adapted to engage said toothed wheel when in its inner position; a cam plate having a plurality of cam projections thereon adapted to engage the checks as they are carried forward by 15 said holder, whereby said check holder is caused to engage said toothed wheel at a predetermined point in its movement; a locking dog for said toothed wheel; a spring for holding said dog normally out of engagement; trip pins on said check holder carrier for said dog, adapted to engage it to throw it into engagement with said toothed wheel at the points of its release by the check holder; a suitable registering mechanism; and driving connections from said toothed wheel to the said registering mechanism, for the purpose specified. 20
35. The combination of a suitable casing; a shaft; a check holder carrier carried by said shaft; a toothed wheel arranged at the side of said check holder carrier; a check holder yieldingly secured to said carrier, adapted to engage said toothed wheel when in its inner position; a cam plate having a plurality of cam projections thereon adapted to engage the checks as they are carried forward by 25 said holder, whereby said check holder is caused to engage said toothed wheel at a predetermined point in its movement; a locking dog for said toothed wheel; a spring for holding said dog normally out of engagement; trip pins on said check holder carrier for said dog, adapted to engage it to throw it into engagement with said toothed wheel at the points of its release by the check holder; a suitable registering mechanism; and driving connections from the toothed wheel to the said registering mechanism, for the purpose specified. 30
36. The combination of a suitable casing; a shaft; a check holder carrier carried by said shaft; a toothed wheel arranged at the side of said check holder carrier; a check holder yieldingly secured to said carrier, adapted to engage said toothed wheel when in its inner position; a cam plate having a plurality of cam projections thereon adapted to engage the checks as they are carried forward by 35 said holder, whereby said check holder is caused to engage said toothed wheel at a predetermined point in its movement; a locking dog for said check holder carrier; a spring adapted to hold said dog normally outward; a stop adapted to engage said dog when said carrier is at the limit of its movement, said locking dog being then in position to be disengaged by the introduction of a check or token; a suitable registering mechanism; and driving connections from said toothed wheel to said registering mechanism, for the purpose specified. 40
37. The combination of a suitable casing; a shaft; a check holder carrier carried by said shaft; a toothed wheel 45 arranged at the side of said check holder carrier; a check holder yieldingly secured to said carrier, adapted to engage said toothed wheel when in its inner position; a cam plate having a plurality of cam projections thereon adapted to engage the checks as they are carried forward by said holder, whereby said check holder is caused to engage said toothed wheel at a predetermined point in its movement; a suitable registering mechanism; and driving connections from the toothed wheel to the said registering mechanism, for the purpose specified. 50
38. The combination of a suitable casing; a shaft; a check holder carrier carried by said shaft; a toothed wheel arranged at the side of said check holder carrier; a check or token holder yieldingly secured to said carrier, adapted to engage said toothed wheel when in its inner position; cam plates having a plurality of cam projections thereon; checks of predetermined values or denominations, adapted to be inserted into said check holder, having notches adapted to engage said cam plates, whereby said check holder is thrown into engagement with the toothed wheel at a predetermined point or points in the movement of said check holder; a locking dog for said toothed wheel; a spring for holding said dog normally out of engagement; trip pins on said check holder carrier for said dog, adapted to engage it to throw it into engagement with said toothed wheel at the points of its release by the check holder; a suitable registering mechanism; and driving connections from said toothed wheel to said registering mechanism, 100 for the purpose specified. 55
39. The combination of a suitable casing; a shaft; a check holder carrier carried by said shaft; a toothed wheel arranged at the side of said check holder carrier; a check or token holder yieldingly secured to said carrier, adapted to engage said toothed wheel when in its inner position; cam plates having a plurality of cam projections thereon; checks of predetermined values or denominations, adapted to be inserted into said check holder, having notches adapted to engage said cam plates, whereby said check holder is thrown into engagement with the toothed wheel at a predetermined point or points in the movement of said check holder; a locking dog for said check holder carrying wheel; a stop adapted to engage said dog when said carrier is at the limit of its movement, said locking dog being then in position to be disengaged by the introduction of a check or token; a suitable registering mechanism; and driving connections from the toothed wheel to said registering mechanism, 110 for the purpose specified. 60
40. The combination of a suitable casing; a shaft; a check holder carrier carried by said shaft; a toothed wheel arranged at the side of said check holder carrier; a check or token holder yieldingly secured to said carrier, adapted to engage said toothed wheel when in its inner position; cam plates having a plurality of cam projections thereon; checks of predetermined values or denominations, adapted to be inserted into said check holder, having notches adapted to engage said cam plates, whereby said check holder is thrown into engagement with the toothed wheel at a predetermined point or points in the movement of said check holder; a locking dog for said check holder carrying wheel; a stop adapted to engage said dog when said carrier is at the limit of its movement, said locking dog being then in position to be disengaged by the introduction of a check or token; a suitable registering mechanism; and driving connections from the toothed wheel to said registering mechanism, 120 for the purpose specified. 65
41. The combination of a suitable casing; a movably supported check or token holder carrier; a movably supported toothed member; a check holder yieldingly secured to said carrier adapted to engage said toothed member when in its inner position; a spring adapted to hold said check holder normally outward; cam plates having a plurality of cam projections thereon; checks or tokens of predetermined values or denominations adapted to be inserted 125 into said check holder, 130
- 80

into said check holder, having notches therein adapted to engage said cam plates, whereby said check holder is thrown into engagement with the said toothed member at a predetermined point in the movement of said check holder; a locking dog for said toothed member; trip pins on said check holder carrier adapted to engage said dog to throw it into engagement with said toothed member at the point of its release by the check holder; a suitable registering mechanism; and driving connections from said toothed member to said registering mechanism, for the purpose specified.

42. The combination of a suitable casing; a movably supported check or token holder carrier; a movably supported toothed member; a check holder yieldingly secured to said carrier adapted to engage said toothed member when in its inner position; a spring adapted to hold said check holder normally outward; cam plates having a plurality of cam projections thereon; checks or tokens of predetermined values or denominations adapted to be inserted into said check holder, having notches therein adapted to engage said cam plates, whereby said check holder is thrown into engagement with the said toothed member at a predetermined point in the movement of said check holder; a suitable registering mechanism; and driving connections from said toothed member to said registering mechanism, for the purpose specified.

43. The combination of a suitable casing; a movably supported check or token holder carrier; a movably supported toothed member; a check holder yieldingly secured to said carrier adapted to engage said toothed member when in its inner position; cam plates having a plurality of cam projections thereon; checks or tokens of predetermined values or denominations adapted to be inserted into said check holder, having notches therein adapted to engage said cam plates, whereby said check holder is thrown into engagement with the said toothed member at a predetermined point in the movement of said check holder; a locking dog for said toothed member; trip pins on said check holder carrier adapted to engage said dog to throw it into engagement with said toothed member at the point of its release by the check holder; a suitable registering mechanism; and driving connections from said toothed member to said registering mechanism, for the purpose specified.

44. The combination of a suitable casing; a movably supported check or token holder carrier; a movably supported toothed member; a check holder yieldingly secured to said carrier adapted to engage said toothed member when in its inner position; cam plates having a plurality of cam projections thereon; checks or tokens of predetermined values or denominations adapted to be inserted into said check holder, having notches therein adapted to engage said cam plates, whereby said check holder is thrown into engagement with the said toothed member at a predetermined point in the movement of said check holder; a suitable registering mechanism; and driving connections from said toothed member to said registering mechanism, for the purpose specified.

45. The combination of a suitable casing; a movably supported check carrier; a movably supported toothed member; a check or token holder yieldingly secured to said carrier, adapted to engage said toothed member when in its inner position; a cam plate having a plurality of cam projections thereon adapted to engage the checks or tokens as they are carried forward by said holder, whereby said check holder is caused to engage said toothed member at a predetermined point; a locking dog for said toothed member; trip pins on said check holder carrier adapted to engage said dog to throw it into engagement with said toothed member at the point of its release by the check holder; a suitable registering mechanism; and driving connections from said toothed member to said registering mechanism, for the purpose specified.

46. The combination of a suitable casing; a movably supported check carrier; a movably supported toothed member; a check or token holder yieldingly secured to said carrier, adapted to engage said toothed member when in its inner position; a cam plate having a plurality of cam projections thereon adapted to engage the checks or

tokens as they are carried forward by said holder, whereby said check holder is caused to engage said toothed member at a predetermined point; a suitable registering mechanism; and driving connections from said toothed member to said registering mechanism, for the purpose specified.

47. The combination of a suitable casing; a registering mechanism; an item or purchase indicator; a pair of movably supported toothed members connected to said registering mechanism and to said item or purchase indicator to actuate the same; a movably supported check holder adapted to connect said toothed members; a cam plate having a plurality of cam projections thereon adapted to engage the checks as they are carried forward by said holder, whereby said holder is caused to engage said toothed members at predetermined points in the movement thereof; and connections from said check holder to said item or purchase indicator whereby the same is reset by the return of the said holder to its initial position, for the purpose specified.

48. The combination of a suitable casing; a registering mechanism; an item or purchase indicator; a pair of movably supported toothed members connected to said registering mechanism and to said item or purchase indicator to actuate the same; a movably supported check holder adapted to connect said toothed members; a cam plate adapted to engage the checks as they are carried forward by said holder, whereby said holder is caused to engage said toothed members at predetermined points in the movement thereof; and connections from said check holder to said item or purchase indicator whereby the same is reset by the return of said holder to its initial position, for the purpose specified.

49. The combination of a suitable casing; a registering mechanism; an item or purchase indicator; a pair of movably supported toothed members connected to said registering mechanism and to said item or purchase indicator to actuate the same; a movably supported check holder adapted to connect said toothed members; and connections from said check holder to said item or purchase indicator whereby the same is reset by the return of the said holder to its initial position, for the purpose specified.

50. The combination of a suitable casing; a registering mechanism; an item or purchase indicator; a pair of movably supported toothed members connected to said registering mechanism and to said item or purchase indicator to actuate the same; a movably supported check holder adapted to connect said toothed members; and a cam plate having a plurality of cam projections thereon adapted to engage the checks as they are carried forward by said holder, whereby said holder is caused to engage said toothed members at predetermined points in the movement thereof, for the purpose specified.

51. The combination of a suitable casing; a registering mechanism; an item or purchase indicator; a pair of movably supported toothed members connected to said registering mechanism and to said item or purchase indicator to actuate the same; a movably supported check holder adapted to connect said toothed members; and a cam plate adapted to engage the checks as they are carried forward by said holder, whereby said holder is caused to engage said toothed members at predetermined points in the movement thereof, for the purpose specified.

52. The combination of a suitable casing; a registering mechanism; an item or purchase indicator; a movably supported check holder adapted to connect said registering mechanism with said item or purchase indicator; a cam plate having a plurality of cam projections thereon adapted to engage the checks as they are carried forward by said check holder, whereby said holder is thrown into engagement with said registering mechanism and with said item or purchase indicator at predetermined points; and connections from said check holder to said item or purchase indicator whereby the same is reset on the return of the check holder to its initial position, for the purpose specified.

53. The combination of a suitable casing; a registering mechanism; an item or purchase indicator; a movably supported check holder adapted to connect said registering mechanism and item or purchase indicator; and connec-

bers, and to engage the outer face of said lug on the return movement of said check holder, for the purpose specified.

66. The combination of a casing; a registering mechanism; an item or purchase indicator; a pair of movably supported toothed members connected to said registering mechanism and item or purchase indicator to actuate the same; a movably supported check holder; a cam plate adapted to connect said toothed members; a locking dog adapted for said toothed members, having an inclined engaging lug thereon; a trip pin connected to said check holder, adapted to engage the inner face of said inclined lug on the forward movement of said check holder to throw said dog into engagement with said toothed members, and to engage the outer face of said lug on the return movement of said check holder; and connections from said check holder to said item or purchase indicator, whereby the same is returned to its initial position on the return of the said check holder to its initial position, for the purpose specified.

67. The combination of a casing; a registering mechanism; an item or purchase indicator; a pair of movably supported toothed members connected to said registering mechanism and item or purchase indicator to actuate the same; a movably supported check holder; a cam plate adapted to connect said toothed members; a locking dog for said toothed members, having an inclined engaging lug thereon; and a trip pin connected to said check holder adapted to engage the inner face of the said inclined lug on the forward movement of said check holder to throw said dog into engagement with said toothed members, and to engage the outer face of said lug on the return movement of said check holder, for the purpose specified.

68. The combination of a casing; a registering mechanism; a movably supported toothed member; a movably supported check holder; a cam plate adapted to engage the checks as they are carried forward by said holder, to throw said check holder into engagement with said toothed member at predetermined points in the movement of said check holder; a locking dog for said toothed member having an inclined engaging lug thereon; a spring adapted to hold said dog normally out of engagement; and a trip pin connected to said check holder adapted to engage the inner face of the said inclined lug on the forward movement of said check holder to throw said dog into engagement with said toothed member and to engage the outer face of said lug on the return movement of said check holder, for the purpose specified.

69. The combination of a casing; a registering mechanism; a movably supported toothed member; a movably supported check holder; a cam plate adapted to engage the checks as they are carried forward by said holder, to throw said check holder into engagement with said toothed member at predetermined points in the movement of said check holder; a locking dog for said toothed member, having an inclined engaging lug thereon; and a trip pin connected to said check holder adapted to engage the inner face of the said inclined lug on the forward movement of said check holder, to throw said dog into engagement with said toothed member, and to engage the outer face of the lug on the return movement of said check holder, for the purpose specified.

70. The combination of a casing; a registering mechanism; a movably supported toothed member; a movably supported check holder; a cam plate adapted to be thrown into engagement with said toothed member by a check carried thereby; a locking dog for said toothed member having an inclined engaging lug thereon; a spring adapted to hold said dog normally out of engagement; and a trip pin connected to said check holder adapted to engage the inner face of the said inclined lug on the forward movement of said check holder to throw said dog into engagement with said toothed member and to engage the outer face of said lug on the return movement of said check holder, for the purpose specified.

71. The combination of a casing; a registering mechanism; a movably supported toothed member; a movably supported check holder; a cam plate adapted to be thrown into engagement with said toothed member by a check carried thereby; a locking dog for said toothed member, hav-

ing an inclined engaging lug thereon; and a trip pin connected to said check holder adapted to engage the inner face of the said inclined lug on the forward movement of said check holder to throw said dog into engagement with said toothed member and to engage the outer face of said lug on the return movement of said check holder, for the purpose specified.

72. The combination of a casing; a registering mechanism; a plurality of cam plates having a plurality of cam projections thereon; and checks of predetermined values having a plurality of notches therein corresponding to the values, adapted to engage said cam plates, whereby said cam plates are engaged at predetermined points to register the value of each check, for the purpose specified.

73. The combination of a casing; a registering mechanism; a plurality of cam plates; and checks of predetermined values, having a plurality of notches therein corresponding to the values, adapted to engage said cam plates, whereby said cam plates are engaged at predetermined points to register the value of each check, for the purpose specified.

74. In a registering mechanism, the combination of the number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; a transfer mechanism for said number wheels, consisting of pinions J'; a shaft for said pinions on which they are slidably mounted; gears J mounted on the hubs of the number wheels I'' and I'''; teeth j' on said number wheels I' and I'', adapted to engage said pinions J', said number wheel I' being provided with one only of said teeth j' and the number wheel I'' being provided with two; teeth or pinions J'' on the hubs of said pinions J', adapted to engage the peripheries of the said number wheels I' and I'''; notches on the peripheries of the said number wheels I' and I''' opposite to said teeth j' to permit the said pinions to advance one step; a lever for shifting the pinions J', having arms engaging the ends of said pinions, said arms having curved engaging portions; and means for securing said lever in its adjusted positions, for the purpose specified.

75. In a registering mechanism, the combination of the number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; a transfer mechanism for said number wheels, consisting of pinions J'; a shaft for said pinions on which they are slidably mounted; gears J mounted on the hubs of the number wheels I'' and I'''; teeth j' on said number wheels I' and I'', adapted to engage said pinions J', said number wheel I' being provided with one only of said teeth j' and the number wheel I'' being provided with two; teeth or pinions J'' on the hubs of said pinions J', adapted to engage the peripheries of the said number wheels I' and I'''; notches on the peripheries of the said number wheels I' and I''' opposite to said teeth j' to permit the said pinions to advance one step; and a lever for shifting the pinions J', having arms engaging the ends of said pinions, said arms having curved engaging portions, for the purpose specified.

76. In a registering mechanism, the combination of the number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; a transfer mechanism for said number wheels, consisting of pinions J'; a shaft for said pinions on which they are slidably mounted; gears J mounted on the hubs of the number wheels I'' and I'''; teeth j' on said number wheels I' and I'', adapted to engage said pinions J', said number wheel I' being provided with one only of said teeth j' and the number wheel I'' being provided with two; teeth or pinions J'' on the hubs of said pinions J', adapted to engage the peripheries of the said number wheels I' and I'''.

wheels I' and I''; and notches on the peripheries of the said number wheels I' and I'' opposite to said teeth j' to permit the said pinions to advance one step, for the purpose specified.

5 77. In a registering mechanism, the combination of the number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; a transfer mechanism for said number wheels, consisting of pinions J'; a shaft for said pinions on which they are slidably mounted; gears J mounted on the hubs of the number wheels I'' and I'''; teeth j' on said number wheels I' and I'', adapted to engage said pinions J', said number wheel I' being provided with one only of said teeth j' and the number wheel I'' being provided with two; and a lever for shifting the pinions J', having arms engaging the ends of said pinions, said arms having curved engaging portions, for the purpose specified.

78. In a registering mechanism, the combination of the number wheels I' I'' and I''', the said wheel I' being divided into twenty spaces numbered 0 to 95 inclusive, the number wheel I'' being divided into twenty spaces numbered in two sets 0 to 9 inclusive, and the number wheel I''' being divided into twenty spaces numbered 0 to 19 inclusive; a transfer mechanism for said number wheels, 25 consisting of pinions J'; a shaft for said pinions on

which they are slidably mounted; gears J mounted on the hubs of said wheels I'' and I'''; teeth j' on said number wheels I' and I'' adapted to engage said pinions J', said number wheel I' being provided with one only of said teeth j' and the number wheel I''' being provided with two; and a lever for shifting the pinions J', having arms engaging the ends of said pinions, said arms having curved engaging portions, for the purpose specified. 35

79. In a registering mechanism, the combination of the number wheels I' I'' and I'''; a transfer mechanism for 40 said number wheels, consisting of pinions J'; a shaft for said pinions on which they are slidably mounted; gears J mounted on the hubs of said wheels I'' and I'''; teeth j' on said number wheels I' and I'' adapted to engage said pinions J', said number wheel I' being provided with one 45 only of said teeth j' and the number wheel I''' being provided with two; and a lever for shifting the pinions J', having arms engaging the ends of said pinions, said arms having curved engaging portions, for the purpose specified. 50

In witness whereof, I, FRANK L. BURDICK, as administrator of the estate of the said LEO J. BURDICK, deceased, have hereunto set my hand and seal in the presence of two witnesses.

FRANK L. BURDICK,
Administrator of the estate of Leo J. Burdick.

Witnesses:

CHAS. A. STURGES,
ARTHUR L. BEEBE.
